OIL WELL TUBING HEAD

Melvin C. Davis, Denver, Colo.

Application September 3, 1953, Serial No. 378,370

1 Claim. (Cl. 251—194)

This invention relates generally to oil well equipment and is directed particularly to improvements in tubing heads.

A particular object of the present invention is to provide an improved tubing head having incorporated therein a novel ram type plug valve by means of which the tubing passage through the head can be tightly sealed off or closed.

Another and more specific object of the invention is to provide a tubing head structure having a valve of the character stated wherein novel means is provided for effecting the tight compression of a packing element between the plug of the valve and adjacent surfaces of the head body after the plug has been disposed in position across the tubing passage or bore, whereby to maintain a tight seal.

A further and more specific object of the invention is to provide in a tubing head structure having a passage or bore through which the well tubing extends, a transversely directed passage intersecting the tubing passage or bore with a cylindrical plug valve in said transverse passage adapted to be disposed therein across the tubing passage and wherein said plug is constructed in a novel manner whereby a body of packing material can be compressed and caused to press tightly against surfaces of the tubing passage and the transverse passage to effect the desired sealing off of the tubing passage.

Other objects and advantages of the invention will become apparent as the description of the same proceeds and the invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in longitudinal section through the improved tubing head of the present invention showing the ram type plug valve partly in side elevation and partly in section, and in closed position.

Figure 2 is a sectional view taken substantially on the line 2—2 of Figure 1.

Figure 3 is a view in perspective of the intermediate or saddle element of the plug valve with the packing element in position thereagainst.

Figure 4 is a detailed section taken substantially on the line 4—4 of the plug valve as shown in Figure 1.

Referring now more particularly to the drawing the numeral 10 generally designates the tubing head of the present invention which comprises an elongate body portion 12 through which is formed the axial bore or passage 14 through which the well tubing, not shown, extends when the head is in working position in oil well apparatus.

At the top and bottom ends of the body 12 are the coupling flanges 16 and 18 respectively, and formed integral with the body 12 are the transversely directed,

2

aligned arms 20 and 22 through which are formed the passages 24 and 26 respectively. These passages are coaxial and form a plug valve chamber having a diameter which is slightly greater than the diameter of the passage 14 as is clearly shown in Figure 2, so that at opposite sides of the passage 14 the sides of the valve chamber cut into the walls of the passage as indicated at 28 in Figure 2.

At the outer end of one of the arms, here shown as the arm 20, there is secured the closure flange 30 which is held in place by bolts 32 in a conventional manner and in between this flange and the end of the arm 20 is a gasket 33.

Upon the inner side of the flange there is formed the inwardly extending stop member or abutment 34, the purpose of which will hereinafter appear.

The outer end of the other arm 22 is likewise closed, but the closure for this arm comprises a circular cap 35, which is provided with a cylindrical socket 36 which aligns with the adjacent passage 26 and between the cap 20 and the end of the arm 22 is a sealing gasket 37 which is compressed by the bolts 38 which secure the cap in position on the end of the arm.

The outer end of the cap is provided with a bore 39 which is eccentrically positioned with respect to the socket 36 and passage 26 and intermediate its ends the wall of the bore 39 is provided with the lubricant channel 40.

A radial passage 41 is provided in the outer end of the cap for the injection of lubricant into the lubricant channel 40 by a suitable means and the outer end of this bore 41 is closed by a plug 42 as shown.

Positioned within the cylindrical chamber formed by the aligned passages 24 and 26 and the socket 36, is the cylindrical plug valve which is generally designated 43 and which is designed to be moved in the chamber to a position where it extends across the tubing passage 14 to close the passage, or to a position where it is retracted with one end in the socket 36, so as to open the tubing passage 14.

The plug valve 43 comprises the two end opposed members 44 and 45 which have their adjacent ends cut-out from the top sides thereof to form the curved recesses or transverse channels 46. These channels extend down through approximately half the diameter of the members 44 and 45 and also extend through the major portion of the length of the members as is clearly shown in Figure 1 and each recess has a short bottom face or floor 46a in which are formed two tapped bolt or screw sockets 47 which are spaced apart transversely of the member as illustrated in Figure 2.

Adapted to position upon the floor surfaces 46a of the two recesses, so as to completely cover the surfaces of the recesses, is the elongate rubber or rubber composition packing element which is generally designated 48 and which, as shown in Figure 3, has the long flat central portion 49 and the upturned end portions 50, the edges of which are rounded as indicated at 51 so as to conform to the external circular contour of the member 44 or 45 in the recess 46 of which it is positioned. Also as will be readily seen upon reference to Figures 2 and 3, the packing element is of a width to extend the full diameter of the plug members 44 and 45 and the overall length of the packing element is greater than the diameter of the tubing passage 14. Thus it will be seen that when the plug is in closing position the side edges of the flat intermediate portion 49 of the packing element will bear against the opposite faces of the plug chamber at opposite sides thereof as shown in Figure 2 and the curved end portions 50 will bear against the surfaces of the upper halves of the passages 24 and 26.

In addition to the members 44 and 45 and the packing

element 48, the plug valve includes a coupling saddle which is generally designated 52 and which, as is clearly shown in Figures 2 and 3 is of slightly less than semi-circular cross sectional form and has a flat-bottom face 53 and rounded ends 54 against which the intermediate portion 49 and end portions 50 of the packing element 51

50 position. This connecting saddle 52 is provided with the transversely spaced pairs of bolt passages 55 which are elliptical in cross section and in which the long axes of the ellipses extend lengthwise of the saddle body and the packing element 48 in the intermediate portion 49 thereof, is formed with similar or matching openings 56 and these openings and the passages 55 match the tapped bolt sockets 47 to receive the threaded ends of holding bolts 57.

The plug member 44 which is nearest to the cap 35 is provided with a longitudinally extending threaded screw passage 58 in which is received the elongate plug actuating screw 59 which has an unthreaded shank portion 60 at its outer end which passes through the bore 39. This shank 60 is squared on its outer end as indicated at 61 to facilitate the application of a suitable tool to the screw for turning the latter.

In line with the threaded passage 58 in the member 44 there is an unthreaded passage 62 formed in the plug member 45 into which the end of the screw may pass to permit the plug to be shifted outwardly or to open position with respect to the tubing passage 14.

In the operation of the present tubing head when it is desired to close off the tubing passage 14 the plug operating screw 57 is rotated in the proper direction to feed the plug valve inwardly toward the stop 34. When the end of the member 45 comes to position against the stop 34, further movement of the plug valve as a whole will be stopped and in this position it will be seen that the periphery of the packing element 48 will have its curved portions 51 on opposite sides of the tubing passage 14, while the portions connecting such curved portions will extend along opposite faces of the chamber in which the plug is located, so that the movement of fluid through the tubing passage 14 past the plug cannot take place.

Due to the fact that the plug members 44 and 45 may have slight movement relative to one another by reason of the form of the bolt passages 55, if it is desired to increase the pressure of the periphery of the packing element against the adjacent wall surfaces, this can be effected by forcing the plug valve member 44 inwardly,

whereby the saddle will also be shifted slightly toward the member 45 and the packing element will be compressed and caused to expand outwardly to increase its sealing contact with the engaged surfaces.

From the foregoing it will be seen that there is provided by the present invention a novel ram type plug valve tubing head structure having a novel plug valve in which the sealing action can be readily controlled.

I claim:

An oil well tubing head comprising a body having a tool and tubing passage therethrough, means carried by the body at each end of said passage for securing the body to and in line with well apparatus, aligned arms integral with said body and extending radially of said passage, 10 said arms having aligned longitudinal passages forming a tubular chamber intersecting the body passage, a closure member at the outer end of each arm passage, a cylindrical valve body slidably positioned in said chamber for movement to a position across the body passage to close the latter, said valve body comprising two spaced cylindrical members having curved recesses formed across the sides thereof and opening through their adjacent ends, a single body of packing material lying in said recesses and bridging the space between the members, a transversely 15 arcuate saddle member lying upon the body of packing material, said body of packing material having a continuous edge lying flush with the cylindrical surface of the valve body, said saddle member having end faces opposing correspondingly formed faces of the recesses, 20 said packing material being pressed between said opposing faces, means loosely coupling the saddle and the cylindrical members whereby relative movement between the same is permitted, the periphery of the packing material being arranged to encircle the body passage when the valve is in closing position thereacross, and means for 25 effecting axial movement of the valve body and for forcing the cylindrical members thereof toward one another when it is in said closing position to effect the compression of the packing element and lateral projection of the 30 periphery thereof beyond the periphery of the valve body members.
